UNITED STATES PATENT OFFICE.

IDA DAVIS, OF SAN ANTONIO, TEXAS.

MILK-BOTTLE CAP.

1,394,409.

Specification of Letters Patent.

Patented Oct. 18, 1921.

Application filed May 6, 1919. Serial No. 295,156.

To all whom it may concern:

Be it known that I, IDA DAVIS, a citizen of the United States, residing at San Antonio, in the county of Bexar and State of 5 Texas, have invented certain new and useful Improvements in Milk-Bottle Caps, of which the following is a specification.

The invention provides a closure for milk bottles, jars and like wide-mouthed receptacles, the purpose being to provide a device which may be readily applied to and easily detached from the bottle and which may be easily cleaned and when in position prevent access to the mouth of the bottle, either 15 by the hand or domestic animals or insects.

The invention furthermore aims to provide a closure which protects the mouth of the bottle and which is secured against being accidentally displaced, but which may be 20 readily removed or placed in position by proper manipulation, the closure being of such formation as to be easily cleaned and free from collecting any matter which would render the device insanitary.

25 The drawing illustrates a preferred embodiment of the invention. However, it is to be understood that in adapting the same to meet different conditions, various changes in the form, proportion, and minor details 30 of construction may be resorted to without departing from the nature of the invention as claimed hereinafter.

Referring to the accompanying drawing, Figure 1 is a side view of the neck portion of a milk bottle or like vessel provided with a closure embodying the invention, the full lines showing the device in closed position and the dotted lines indicating one-half of the closure in open position.

40 Fig. 2 is a top view.

Fig. 3 is a view similar to Fig. 1 as seen from the reverse side.

Fig. 4 is a view of the closure inverted.

Fig. 5 is a section on the line 5-5 of 45 Fig. 2.

Corresponding and like parts are referred to in the following description and indicated in the several views of the drawing by like reference characters.

50 The numeral 1 designates a milk bottle, jar or analogous wide-mouthed receptacle. The closure is designed chiefly for a receptacle of the character indicated and comprises similar sections 2 and 3. These sections are hingedly connected at 4 and each

comprises a top and a depending rim, the latter being of a depth to inclose the top portion of the neck and thereby prevent the hand from coming in contact with the neck, or a domestic animal from lapping the same 60 as frequently occurs, besides preventing insects from lighting on the neck portion of the bottle. The rim portion of the closure is downwardly converging so as to underlap the usual bead or enlargement provided 65 at the mouth of the bottle for reinforcing and strengthening the same. In this manner the closure when in position is prevented from displacement. It is to be understood that the bottles or jars are of standard 70 sizes, hence the closures will likewise be made of a standard size for effective co-operation with the bottles or like receptacles.

The section 2 is provided at opposite ends of its depending rim with studs 5. The 75 depending rim of the section 3 is provided with arms 7 to receive the studs 5 at the corresponding ends of the depending rim of the section 2. Arms 7 project from ends of the depending rim of the section 3 and 80 are curved concentric with the hinge, as shown most clearly in Fig. 3. The arms 7 are slotted and the slots 7^a receive the studs 5 at the corresponding ends of the rim of the section 2. The arms 7 constitute means for 85 holding the section 3 in open position, as indicated by the dotted lines in Figs. 1 and 3. The arms 7 frictionally engage the head of the studs 5 and the side of the rim of the section 2 and this frictional resistance is 90 sufficient to hold the section 3 open in any adjusted position within its range of movement, the latter being determined by the closed end of the slots 7^a engaging the cooperating studs 5. The studs 5 are headed 95 so as to overlap the sides of the slots 7^a and retain the arms in given position.

The section 2 comprises a top which is of a size to extend over the top of the bottle or jar 1. This top comprises an outer portion 8 and a central portion 9, the latter being elevated and adapted to receive a stopper 10 which is fitted therein, as indicated most clearly in Fig. 5. A fastening 11 secures the stopper 10 to the elevated portion 100 105 9 and the stopper may be of rubber, cork or other material generally employed as sealing means for bottles and like containers. The section 3 embodies a top portion 12 which overlaps one-half of the part 8 of the 110

section 2 and is disposed exterior to the elevated portion 9. The overlapping portion 12 consists of a semi-circular flange.

It is proposed to construct the device of 5 any suitable material such as aluminum or other sheet metal which may be stamped or pressed into the required shape. When placing the closure in position the section 10 3 is moved into open position and the section 2 is fitted about the neck of the bottle after which the section 3 is closed and by reason of the converging formation of the 15 depending rims of the two sections, said rim closes about the neck of the bottle beneath the beaded edge thereof, thereby preventing 20 displacement of the closure. The stopper 10 projects slightly below the central portion 9 so as to enter the mouth of the bottle. This 25 is indicated most clearly in Fig. 5.

20. The foregoing description and the drawings have reference to what may be considered the preferred, or approved form of my invention. It is to be understood that I may make such changes in construction and arrangement and combination of parts, materials, dimensions, et cetera, as may prove expedient and fall within the scope of the appended claims.

Having thus fully described my invention, what I claim as new and desire to secure by Letters Patent is:—

1. A closure for milk bottles and like

wide-mouthed receptacles comprising two similar sections, each embodying a top and a depending rim, hingedly connected by 35 means of their top portions and having the ends of the rim overlapping when in closed position, an arm projecting from the outer end of one of the rims and curved concentric with the hinged joint between the two 40 sections, and a stud on the inner end of the other rim to coöperate with the said arm to hold the relatively movable section open in adjusted position.

2. A closure for milk bottles and like 45 wide-mouthed receptacles comprising two similar sections each embodying a top and a depending rim, hingedly connected by means of their top portions, the rims converging downwardly to fit about the bead 50 or enlargement at the mouth of the bottle, curved arms projecting from the ends of one of the rims, and studs projecting from the ends of the other rim and coacting with the said arms to hold the relatively movable 55 section open in the required adjusted position.

In testimony whereof I affix my signature in presence of two witnesses.

IDA DAVIS.
